UNITED STATES PATENT OFFICE.

GEORGE A. BODEE, OF NEW YORK, N. Y.

LAMP-BURNER.

SPECIFICATION forming part of Letters Patent No. 593,454, dated November 9, 1897.

Application filed July 31, 1897. Serial No. 646,607. (No model.)

To all whom it may concern:

Be it known that I, GEORGE A. BODEE, of New York city, in the county and State of New York, have invented a new and Improved 5 Lamp-Burner, of which the following is a full, clear, and exact description.

This invention relates to burners for oil-lamps; and the object is to provide a burner with a chimney-gallery having a removable portion underneath the chimney, whereby by moving said movable portion to an open position a match may be inserted for lighting the wick, thus rendering it unnecessary to lift or remove the chimney.

15 I will describe a lamp-burner embodying my invention, and then point out the novel features in the appended claims.

Reference is to be had to the accompanying drawings, forming a part of this specification, 20 in which similar characters of reference indicate corresponding parts in all the views.

Figure 1 is a perspective view of a lamp-burner embodying my invention. Fig. 2 is a bottom plan view, and Fig. 3 is a top plan 25 view, showing the movable portion as open.

On the burner 1 is mounted a gallery-base consisting of two segmental sections 2 3. The section 2 is rigidly attached to the burner, and the section 3 is mounted to swing relatively thereto. As here shown, the section 3 has a pivotal connection 4 with the section 2, so as to swing on a horizontal plane. Extended outward from the fixed section 2 is an arm 5, having a finger-plate 6 on its end, and 35 extended outward from the movable section 3 is an arm 7, having a finger-plate 8 on its end. A spring 9 is connected at one end to the arm 5 and at the other end to the arm 7. This spring serves to hold the movable portion of the gallery-base yieldingly in its closed 40 position.

Extended upward from the fixed section 2 are pairs of chimney-holding fingers 10 11. The inner fingers 10 are designed to engage the inner side of a chimney, and the fingers 45 11 are designed to engage the outer surface of the chimney. By this construction it is obvious that lateral displacement of the chimney will be prevented.

In operation when it is desired to light the 50 wick a pressure on the arms 5 and 7 will swing the section 3 outward, as indicated in Fig. 3, so that a match may be inserted through the lower end of the chimney.

For the purpose of bracing the movable portion 3 a plate 12 is attached to the burner and engages against the under side of the movable portion, and as a further means of support the free end of the movable portion may be made to overlap the end of the fixed portion.

Having thus described my invention, I claim as new and desire to secure by Letters Patent—

1. The combination with a lamp-burner, of 65 a chimney-gallery comprising a fixed section, a horizontally-swinging section, arms extended from the sections, and a spring for holding the swinging section yieldingly in its closed position, substantially as specified. 70

2. The combination with a lamp-burner, of a chimney-gallery having a base consisting of a fixed section and a swinging section, arms extended from the sections, a spring connecting the sections, and chimney-holding fingers 75 on the fixed section, substantially as specified.

GEORGE A. BODEE.
